Primary Examiner — Paula Allen Greene(74) *Attorney, Agent, or Firm* — Viering, Jentschura & Partner mbB(57) **CLAIM**

The ornamental design for earphones as shown and described.

DESCRIPTION

FIG. 1 is a perspective view of earphones showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the Figures show portions of the earphones that form no part of the claimed design. The earphones are shown with a symbolic break in the earphone cord in FIGS. 1 through 7. The appearance of any portion of the earphones between the break lines form no part of the claimed design.
